(57) **CLAIM**

The ornamental design for a mobile cart, as shown and described.

DESCRIPTION

The present application claims priority from U.S. Provisional Patent Application No. 62/979,953 filed Feb. 21, 2020.

FIG. 1 is a top, back and right side perspective view of a mobile cart;

FIG. 2 is a top, front, and left side perspective view of a mobile cart;

FIG. 3 is a right view of the mobile cart;

FIG. 4 is a left view of the mobile cart;

FIG. 5 is a front view of the mobile cart;

FIG. 6 is a back view of the mobile cart;

FIG. 7 is a top view of the mobile cart; and,

FIG. 8 is a bottom view of the mobile cart.

The dash-dash broken lines in the figures show portions of the mobile cart which form no part of the claimed design. The dash-dot broken line define the bounds of the claimed design and form no part thereof.
